STEAM-TURBINE.

1,117,969.

Specification of Letters Patent.

Patented Nov. 17, 1914.

Application filed June 25, 1913. Serial No. 775,760.

To all whom it may concern:

Be it known that I, THOMAS RIGBY, a subject of the King of Great Britain and Ireland, and residing at Kelton House, Dumfries, Scotland, have invented certain new and useful Improvements in and Relating to Steam-Engines or Steam-Turbines, of which the following is a specification.

This invention relates to steam power installations and has for its object to enable economies to be effected in the operation thereof by the employment in a particular manner in heating devices of steam which has already performed work in the prime mover.

The invention consists broadly in utilizing steam exhausted from the prime mover partly to heat the air for the furnace of the steam generator, and partly in performing further work.

In the accompanying drawing there is shown diagrammatically an installation for carrying the invention into effect in which the steam is generated in a steam boiler *a* by the combustion of a fuel in a combustion chamber or furnace *b*. On opening a controlling valve *c* steam passes from the boiler to the main steam pipe *d* and from thence on opening a valve *e* it is admitted to the prime mover *f* which in the case illustrated is a steam turbine. After having performed work in the high pressure stage or stages *g* of the turbine, some of the steam is taken through a pipe *h* to a heater *k* through the tubes *m* of which there passes air which flows through the duct *n* to the combustion chamber *b* of the steam boiler *a*, so that the air necessary for combustion of the fuel in the chamber *b* is preheated by condensation of steam in the heater *k*. The remainder of the steam not thus utilized passes through the low pressure stages *p* of the turbine *f* where it is caused to perform further work, and is thereafter exhausted through a conduit *q* into a condenser *r*. From the latter the condensate is taken by a pipe *s* along with that coming from the heater *k* by a pipe *t* to a single pipe *u* leading to an injector *v* by which all the condensate is returned to the boiler *a*. By thus heating the air by the condensation of an appropriate proportion of the exhaust steam not only is heat imparted to the air, but by returning the hot condensate to the

steam generator a large amount of heat is saved, with result that the portion of the power represented more or less by the proportion of the whole of the steam which is passed to the heater, is generated with extremely high heat efficiency, such that the economy of the plant as a whole is very materially increased.

The temperature to which the air is heated will depend upon the pressure at which the steam is allowed to pass to the heater, and likewise the heat economy obtained, but in order to maintain as high as possible the amount of hot condensate available for returning to the boiler it is preferable to employ saturated steam, as in this way lubricants, and consequently their removal from the condensates, can in most cases be avoided. A further advantage obtained by thus heating the air for the steam generator is that the feed water may be heated by the flue gases in the well-known manner which has proved itself so efficient in the past, this economy being in addition to that which results from effecting combustion in the steam generator furnace at an increased temperature which causes an increased boiler output and efficiency.

Having now described my invention, what I claim as new and desire to secure by Letters Patent is:—

1. A method of economizing heat in steam power installations consisting in generating steam from heat produced by combustion, causing said steam to perform useful work by a reduction of its pressure, then utilizing part of the steam of reduced pressure to heat one of the elements used in said combustion, and the other part of the steam in performing further useful work.

2. A method of economizing heat in steam power installations, consisting in generating steam from heat obtained by combustion of a fuel, causing said steam to perform useful work by a reduction of its pressure, then utilizing part of the steam of reduced pressure to heat the air for combustion of said fuel, and the other part of the steam in performing further useful work.

3. A steam power installation comprising in combination a steam generator heated by combustion of a fuel, a high and a low pressure prime mover and means for heating the air for the combustion of said fuel, said

means being heated by steam exhausted from the high pressure prime mover.

4. A steam power installation comprising in combination a steam generator heated by combustion of a fuel, a high pressure prime mover receiving steam from said generator, means for heating the air necessary for combustion of said fuel, said means being heated by steam exhausted from the prime mover, and a low pressure prime mover in which the steam not required in the heating means is caused to perform further work.

5. A steam power installation comprising in combination a steam generator heated by combustion of a fuel, a high pressure prime mover receiving steam from said generator, means for heating the air necessary for combustion of said fuel, said means being heated by steam exhausted from the prime mover, a low pressure prime mover in which the steam not required in the heating means is caused to perform further work, and means for returning to the steam generator

the condensate from the air heating means and the low pressure prime mover.

6. A steam power installation comprising in combination a steam generator having a combustion chamber, a turbine having high and low pressure stages to the former of which steam is supplied from the generator, a heater receiving part of the steam which has passed through the high pressure stages of said turbine, means by which the air necessary for combustion of the fuel in the combustion chamber of the generator is passed thereto by way of said heater, and a condenser to which the remainder of the steam after having passed through the lower pressure stages of the turbine is delivered.

In testimony whereof I have signed my name to this specification in the presence of two subscribing witnesses.

THOMAS RIGBY.
